UNITED STATES PATENT OFFICE.

WALTER CHARLES YUND, OF AMSTERDAM, NEW YORK.

POCKET CONSTRUCTION AND METHOD OF MAKING SAME.

Application filed June 9, 1928. Serial No. 284,268.

This invention relates to a pocket construction for garments, and particularly garments of knit material, such as sweaters, knit coats, and the like. The knitted cloth in such garments is generally thick and heavy, and considerable difficulty exists in applying a pocket thereto. Various methods are in use, but, as a rule, they are more or less unsatisfactory and involve considerable hand work in knitting or stitching the pockets in place on the garment, thus making the operation slow and expensive. Also, as a rule, pockets as previously made are more or less elastic around the opening thereof, so that they soon sag or stretch out of shape. The present invention aims to provide a construction in which the pockets can be applied to the garment in a simple and rapid manner by the use of machinery and in which practically no hand work is necessary.

A further object is to provide a pocket in which the pocket opening is entirely surrounded by a strip of re-enforcing material, thus making it practically impossible to stretch the opening or pull it out of shape.

A still further object is to provide a construction of the kind just mentioned in which the pocket can be applied without producing a thick and bulky seam around the pocket opening.

A further object of the present construction is that the pocket used can be made of knitted material having a finer weave than the garment material so that the pocket is lighter and stronger and less subject to stretching than the material of the garment.

Various other objects of the invention will appear from the following detailed specification taken in connection with the accompanying drawings in which:

Figure 1 is a plan view of the front or right side of a portion of the garment material illustrating the first stage in the formation of a pocket according to the present invention;

Figure 2 is a vertical section on the line 2—2 of Fig. 1;

Figure 3 is a plan view showing a further stage in the production of a pocket according to the present invention;

Figure 4 is a vertical section on the line 4—4 of Fig. 3;

Figure 5 is a plan view of the front or right side of a part of the garment showing a still further stage in the production of the pocket;

Figure 6 is a vertical section on the line 6—6 of Fig. 5;

Figure 7 is a vertical section on the line 7—7 of Fig. 5;

Figure 8 is a view from the front or right side of the garment illustrating the appearance of the same after the portions of the pocket have been forced through the pocket slit, as hereinafter described;

Figure 9 is a detailed view showing the construction at the upper corners of the pocket;

Figure 10 is a plan view looking toward the rear or wrong side of the garment and the pocket after the pocket has been applied thereto; and

Figure 11 is a vertical section on the line 11—11 of Fig. 10.

Referring to the drawings in detail, 10 indicates a portion of the garment cloth or material in which the pocket is to be formed, the front face or right side of the garment cloth appearing in this view. As a first step in forming a pocket, a piece of pocket material is laid on the front or right side of the garment cloth and directly in contact therewith. This pocket forming material comprises a single piece, but for convenience of description, it will hereinafter be referred to as consisting of the upper and lower portions respectively indicated at 11^a and 11^b. A strip of narrow tape 12 is next placed upon the pocket piece 11^a, 11^b, and extends transversely of the same intermediate its ends, this tape being of relatively strong and non-elastic material. A narrow strip of any strong non-elastic material will answer the purpose of this tape. The tape 12 is preferably provided with free ends 12^a, 12^b, which extend a slight distance beyond the edges of the pocket forming piece 11^a, 11^b.

The cloth of the garment and the pocket piece 11^a, 11^b, and the tape 12 are sewed together by two lines of through-and-through stitching, an upper line 13^a and a lower line 13^b, which extend longitudinally of the tape 12. Extending between the longitudinal lines of stitching, 13^a and 13^b, are transverse lines of stitching 13^c and 13^d. The longitudinal and transverse stitching serves to securely fasten the tape 12 and the pocket material 11^a, 11^b, to the cloth of the garment.

After the parts are fastened together as described, a slit 14 is made longitudinally of the tape 12, which slit extends through the tape, the pocket forming material, and the

material of the garment. It forms the pocket opening. The slit 14 terminates at each end a little short of the transverse stitching 13^a, 13^b, and in effect it divides the tape or strip 12 into an upper portion 12^c and a lower portion 12^d. These portions of the tape together with the uncut ends thereof form a re-enforcing strip extending entirely around the slit or pocket opening 14. The construction at this stage constitutes in effect a blank having the upper and lower portions 11^a, 11^b, the adjacent edges of which are substantially flat or unfolded, this blank being subjected to further operations in the formation of the pocket.

After the slit 14 is formed, the cut edges of the material at the upper and lower sides of the slit are cover-seamed as illustrated particularly at 15 and 16 in Figures 5, 6 and 7. This cover-seaming operation may be performed by any well-known machine adapted for that purpose. As illustrated in said Figures 6 and 7, the cover-seaming 15 and 16 overlies the seams or cut edges of the material and respectively takes in the upper and lower portions 12^a and 12^b of the tape. In this operation of cover-seaming, the edges of the cloth are mashed down and flattened out more or less, so that the seams are very strong and non-elastic due to the cover-seaming and due to the fact that a re-enforcing strip is included in the seam at both the top and bottom and around the ends of the slit or pocket opening 14. The condition of the parts after such cover-seaming operation has been performed is illustrated in Figure 5 and also in section in Figures 6 and 7.

In the next operation the pocket portions 11^a and 11^b are forced through the slit or pocket opening 14. The free ends 12^a and 12^b of the tape are also forced through such opening. This condition of the parts is illustrated in Figure 8 showing the front or right side of the garment cloth and showing the pocket in dotted lines on the rear side thereof.

In forcing the pocket portions 11^a and 11^b through the opening, the edges of the opening and the edges of the upper and lower pocket portions are turned or bent inwardly more or less so that the cover stitching appears on the inside or wrong side of the garment, and the outside of the garment is relatively smooth and even and shows little or no bulkiness and no stitching except certain stitches of the cover-seaming which are visible on the front or right side of the garment and illustrated at 15^a and 16^a.

After the upper and lower portions of the pocket are thus forced through the slit or pocket opening 14, the edges of the pocket portions are sewed together preferably by suitable overstitching 17 extending down the sides and across the bottom of the pocket. By this means the bag of the pocket is formed.

As previously noted, the free ends 12^a and 12^b of the tape are also turned inwardly when the pocket portions are turned inwardly, and these free ends of the tape are preferably laid between the edges of the pocket as illustrated particularly in Figure 9, and when the overlapping edges of the pocket portions are sewed together, these free ends of the tape are sewed into the seam, which fastens the edges of the pocket portions together. This arrangement serves to greatly strengthen the pocket at the ends of the opening and prevent any tearing at that point. As a further precaution, after the parts are finished as above indicated, butt stitching, indicated at 18, may be applied at each end of the pocket opening, which serves to further strengthen the same at these points.

Viewing the completed pocket, as it appears in cross section particularly in Figure 11, it will be seen that the cloth of the garment at the upper edge of the pocket slit or opening is turned inwardly and that the upper edge of the pocket portion 11^a is turned inwardly also, and that the stitching 13^a extends through both the garment cloth and the pocket material and also through the re-enforcing strip 12^c. It will also be seen that at the lower edge of the pocket the material of the garment is turned inwardly or rearwardly, and the upper edge of the pocket portion 11^b is turned outwardly. These latter turned parts are connected by the stitching 13^b which extends through both the garment cloth and the pocket material and also through the re-enforcing strip 12^d. It will also be clearly seen from this figure that the overstitching 15 serves to cover and securely lock the rear pocket portion 11^a to the upper edge of the pocket opening and that the overstitching 16 serves to securely lock the front pocket portion 11^b to the lower edge of the pocket opening.

Preferably the bottom of the pocket is stitched to the body of the garment as illustrated at 19 in Figure 11.

The invention is obviously capable of modification as to various details, and it is understood not to be limited except as set forth in the appended claims.

Having thus described the invention, what is claimed as new and desired to be secured by Letters Patent is:

1. The method of forming a pocket of knitted material in garments of knitted cloth which consists in placing upon the front side of the garment cloth a piece of material to form the pocket, placing on top of the pocket-forming piece intermediate its ends a narrow strip of strong relatively non-elastic material, sewing said parts together by a line of stitching extending longitudinally along each edge of said strip and transversely thereof adjacent each edge of the pocket-forming piece, cutting a slit longitudinally

of said strip between the longitudinal lines of stitching therein and terminating short of the transverse stitching at each end, said slit extending through said strip, and 5 through the pocket-forming piece and the garment cloth, forcing the portions of the pocket-forming piece on each side of said slit through the slit to the rear side of the garment cloth, and securing said portions together on the rear side of the garment cloth.

2. The method of forming a pocket in garments of knitted cloth which consists in placing directly upon the front side of the garment cloth a piece of material to form the pocket, placing on top of the pocket-forming piece intermediate its ends a narrow strip of strong relatively non-elastic material, sewing said parts together by a line of stitching extending longitudinally along each edge of 15 said strip, placing on top of the pocket-forming piece intermediate its ends a narrow strip of strong relatively non-elastic material, sewing said parts together by a line of stitching extending longitudinally along each edge of said strip and transversely thereof adjacent each edge of the pocket-forming piece, cutting a slit longitudinally of said strip between the longitudinal lines of stitching therein and terminating short of the transverse stitching 20 at each end, said slit extending through said strip, and through the pocket-forming piece and the garment cloth, applying cover-seam stitching to the upper and lower cut edges of said slit to bind and cover the same, said 25 upper and lower stitching including respectively the upper and lower portions of said strip, forcing the portions of the pocket-forming piece on each side of said slit through the slit to the rear side of the garment cloth, and securing said portions together on the 30 rear side of the garment cloth.

3. The method of forming a pocket in garments which consists in placing directly upon the front side of the garment cloth a piece 40 of material to form the pocket, placing on top of the pocket-forming piece intermediate its ends a narrow strip of strong relatively non-elastic material, sewing said parts together by a line of stitching extending longitudinally along each edge of said strip and 45 transversely thereof adjacent each edge of the pocket-forming piece, said strip at each end having a free part extending beyond said transverse stitching, cutting a slit longitudinally of said strip between the longitudinal lines of stitching therein and terminating short of the transverse stitching at each end, said slit extending through said strip, and 50 through the pocket-forming piece and the garment cloth, forcing the portions of the pocket-forming piece on each side of said slit through the slit to the rear side of the garment cloth, forcing the free parts of said strip through said slit and positioning the 55 same between the edges of said pocket portions and sewing the edges of the pocket portions and the said free parts of said strip together.

4. The herein described pocket construction 60 for garments, comprising in combination

with the cloth of the garment having a slit therein, the upper and lower edges of which are turned inwardly, a rear pocket portion having its upper end turned inwardly and positioned against the inturned upper edge of 70 said slit, a re-enforcing strip positioned on the rear side of the upper edge of said rear pocket portion, through-and-through stitches securing together said strip, said inturned upper edge of the rear pocket portion and 75 the inturned upper edge of the slit, a front pocket portion having its upper edge turned forwardly and abutting the inturned lower edge of said slit, a re-enforcing strip positioned on the upper edge of said front pocket 80 portion and on the side thereof away from the inturned lower edge of said slit, through-and-through stitches securing together said strip, said outwardly turned upper edge of 85 the front pocket portion and the inturned lower edge of said slit.

5. A construction as defined in claim 4 in which said re-enforcing strips are provided at each end with extensions which extend downwardly and are secured between the 90 edges of the front and rear pocket portions.

6. A construction as defined in claim 4 in which the inturned upper and lower edges of the slit and the inturned upper edge of 95 the rear pocket portion and the out-turned upper edge of the front pocket portion are overlaid by overseam stitching which extends over the seams and through the garment material and pocket material on opposite sides of said seams.

7. A blank for use in forming a pocket in the material of a knitted garment, said blank comprising an upper pocket portion having a substantially flat lower edge, a strip of strong relatively inelastic tape extending 105 along said lower edge with through-and-through stitches securing said tape and pocket portion to the material of the garment and said blank also comprising a lower pocket portion having a substantially flat upper edge 110 and also having a strip of strong relatively inelastic tape extending along said upper edge with through-and-through stitches securing said last named strip of tape and said upper edge of the lower pocket portion to 115 the material of said garment, the material of said garment being provided with a slit extending transversely of said pocket portions between said lower edge of the upper pocket portion and the upper edge of said lower pocket portion.

8. The method of forming a pocket in garments of knitted cloth which consists in placing upon the front side of the garment cloth a piece of material to form the pocket, placing on top of the pocket-forming piece intermediate its ends a narrow strip of strong relatively non-elastic material, sewing said parts together by a line of stitching extending longitudinally along each edge of said 125 strip.

strip, cutting a slit longitudinally of said strip between the longitudinal lines of stitching therein, said slit extending through said strip, and through the pocket-forming piece 5 and the garment cloth, forcing the portions of the pocket-forming piece on each side of said slit through the slit to the rear side of the garment cloth, and securing said portions together on the rear side of the garment 10 cloth.

9. A blank for use in forming a pocket in knitted garment material, said blank comprising an upper pocket portion positioned on said garment material and having a strip 15 of strong relatively inelastic tape extending along its lower edge on the face thereof opposite the garment material, through-and-through stitches securing said tape and pock-

et portion to the garment material, said blank also comprising a lower pocket portion positioned on said garment material and having a strip of strong relatively inelastic tape extending along its upper edge on the face thereof opposite the garment material, through-and-through stitches securing said last named strip of tape and said upper edge of the lower pocket portion to the garment material, the garment material being provided with a slit extending transversely of said pocket portions between said lower edge 30 of the upper pocket portion and said upper edge of said lower pocket portion.

In testimony whereof I hereunto affix my signature.

WALTER CHARLES YUND.
